METAL PLANK

Angus S. MacDonald, near Rapidan, Va., assignor
to The Globe Wernicke Co., a corporation of
Ohio

Application April 16, 1946, Serial No. 662,504

6 Claims. (Cl. 189—34)

1

This invention relates to improvements in metal planks of the character used in building construction to provide a building unit therefor, either for inside or outside building walls, panels, floors, or other parts of the building.

In the construction of buildings, it has been the practice generally heretofore to form the wall or floor units of studding or sills with plaster or wood covering applied thereover, in a fabricated structure. Some attempts have been made to provide panel units, especially for pre-fabricated buildings, but these have not been entirely satisfactory, because of the considerable weight that is objectionable in transportation and handling, or the complexity of structure that renders the units expensive to manufacture and use. Furthermore, such panels usually have required nailing or other fastenings at the joints thereof, which did not facilitate the assembly and connection of the panel units in a simple and expeditious manner.

One object of this invention is to improve the construction of a building unit or plank to provide a sturdy and rigid construction which is, nevertheless, of light weight, that is adaptable to various finishes for an attractive appearance and yet is very practical to use because of its supporting qualities, as well as its insulating effect against heat or cold.

In accomplishing this object, I prefer to construct the plank or building unit with spaced walls joined together to provide an enclosure which will serve not only as a dead air space, but may receive therein insulating material that will insulate effectively the plank or building unit against the passage therethrough of heat or cold. Moreover, the construction, preferably of metal, also interconnects the side walls thereof, but without the direct transfer of heat through conduction along the plank or unit from one side wall to the other, thus further increasing the insulating effect of the unit. The side walls, being formed of sheet-metal, are capable of decoration to any desired extent without requiring the use of plaster or other supporting material for the decorating effect.

A further object of the invention is to improve the construction of the joint between adjacent planks or building units, whereby these may be interconnected readily and yet effectively, without the necessity for using fastenings for securing the parts in place. This is particularly important in the construction of pre-fabricated buildings where the wall and floor units should be fitted together without the necessity for cutting and fitting during the erection process.

2

In constructing the plank or building unit of sheet-metal, provision may be made at the edges thereof for the interfitting of the adjacent planks in a simple and effective manner through a resilient connection between the edges that will make a tight joint, even without the necessity for the use of separate fastenings. This is made possible by providing rounded spring connections and interfitting sockets on the respective opposite edges of the planks, whereby a spring tongue on one edge of one plank will interfit with a socket on the adjacent edge of the next adjacent plank. These tongues and sockets are provided preferably on both opposite sides of each plank, whereby the tongues on one plank will embrace the edge portion of the adjacent plank and hold it securely, that will be effective to provide a tight joint, but without the necessity for the use of fastenings therebetween.

20 The invention is illustrated in certain embodiments thereof, in the accompanying drawings in which:

Fig. 1 is a perspective view showing a joint between interconnected planks made in accordance with this invention;

25 Fig. 2 is a top plan view illustrating the end construction of the planks;

Fig. 3 is a detail elevation showing an edge of a plank;

Fig. 4 is a side elevation of a wall formed by an 30 assembly of planks;

Fig. 5 is a horizontal sectional view through an intermediate portion of a plank;

Fig. 6 is a detail cross section through an edge of the plank showing a modified connection 35 therein;

Fig. 7 is a cross section through a joint between planks showing a further modified construction;

Fig. 8 is a diagrammatic end view showing one 40 method of assembling the planks;

Fig. 9 is a detail transverse section showing a further modified form of plank; and

Fig. 10 is a similar view of the opposite edge of the plank showing still another modification thereof.

45 While the invention may be used in many different applications in building construction, such as for walls, floors, ceilings, and other parts thereof, it is described more particularly as applied to a wall construction merely for purpose of illustration and because its more immediate application appears to be in the construction of walls of pre-fabricated buildings.

A wall will be formed preferably of a plurality of upright planks arranged in edge-to-edge relation, as shown in Fig. 4, in which adjacent planks

are designated generally at 1 and 2, and succeeding planks at 3 and 4. These planks may be constructed, respectively, according to this invention, and interconnected in edge-to-edge relation to form the desired wall or other part of the building. For a wall, the planks extend preferably throughout the height of the wall, usually of one story height, although it is possible to construct them so that they will extend to a height of two or more stories, if that should be desired. Where the planks are used in pre-fabricated buildings and the length is to be that of one story, these may be constructed of selected lengths which will vary ordinarily from seven feet to ten feet, according to the height of the building story and the use thereof, as for outside or inside walls. For most pre-fabricated buildings, a width of twelve inches is preferred, because of its adaptability to fitting in different building plans. For these dimensions, a thickness of about six inches has been found practical for manufacture. These dimensions are given, however, merely for purpose of illustration of a construction that is adaptable for factory manufacture in pre-fabricated building construction and, of course, the invention is not limited as to size or proportions of the planks.

The planks 1 and 2 are shown interconnected in Figs. 1 and 2. Each of these is shown as constructed in like manner and only one need be described in detail.

Each plank is shown as formed in two sections, preferably made of sheet-metal, such as steel, aluminum, or other prefabricated materials. It is preferred to use cold rolled sheet aluminum alloy for the purpose, because of its lightness in weight and adaptability to be fabricated, as well as having a stiff springiness that will facilitate the connection of the planks at the joints therebetween, as hereinafter described.

Each of the plank sections has opposite side walls, as indicated at 5 and 6, respectively, which walls extend substantially parallel in spaced relation and may be corrugated, as illustrated in Figs. 1, 2 and 4, or plane, as shown in Fig. 5, whichever is desired, according to the use and ornamental effect to be obtained. The wall section 5 has inturned end sections 7 and 8, projecting inwardly from the opposite end portions of the wall. The wall 6 has corresponding inturned end sections 9 and 10, substantially in transverse alignment with the end sections 7 and 8, respectively. The opposed end sections are preferably shaped at acute angles to each other, so that the end sections of adjacent boards are arranged substantially in diamond shape, as shown in Fig. 2, providing external grooves in the respective boards to accommodate the fastenings between the sections of each board.

The respective side wall sections of each board are connected together, through crimped joints or wooden connections, in which insulating means is preferably incorporated as hereinafter described. Each of these joints is shown as formed by an outturned flange 11 formed on the respective end sections 8 and 10, and embraced by a folded-over crimped flange 12 that extends therearound, as shown in Fig. 2. These parts may be held in spaced relation for insulating effect, as hereinafter described, but will effectively secure the side wall sections together and hold the parts of the board in secure assembly. These crimped joints may be bent transversely in serpentine fashion, as indicated at 13 in Fig. 3, if desired, to increase the holding effect therebetween, of the sections.

The top and bottom sides of the plank are partially closed by diaphragms 14, fitting in the respective sections of the plank with their inner edges spaced from each other, as will be evident from Figs. 1 and 2. Each of the diaphragms 14 is formed with a surrounding flange 15 thereon, fitted in abutting relation with the corresponding side wall section to increase the stiffness of the diaphragm and the bracing effect thereof on the plank. While the diaphragm stiffness 14-15 may be welded to the plank sections, if desired, I have shown a punched and rolled connection, generally indicated at 16, therebetween, formed by a tool which punches through the sheet-metal forming the end section of the plank and the adjacent portion of the flange 15 on the diaphragm, and which tool also rolls the punched-out metal into a tight roll that will hold the parts securely together.

Additional diaphragm stiffeners may be provided at intervals along the length of each plank, as indicated at 14' in Figs. 1 and 3, and secured in place by similar punched and rolled connections 16'. These intermediate diaphragms will reinforce and strengthen the plank intermediate the ends thereof. The number and spacing of these intermediate diaphragm stiffeners will depend somewhat upon the use of the plank, but ordinarily a spacing of about eighteen inches will be sufficient for wall construction, although somewhat closer spacing will be required where the plank is used for a floor construction.

It will be noted that the diaphragm stiffeners 14, 14' are secured at the respective opposite edges of the plank, while they abut the side faces 5 and 6 of the plank in such a way as to stiffen the whole structure without requiring any fastening through the plank faces. However, these stiffeners may be welded at the flanges 15, if desired, to the side faces 5 and 6.

To provide for an interfitting joint between the boards or building units, I have provided a yieldable tongue and groove connection therebetween at the respective opposite sides of each board. Each of the end sections 8 and 9, at the juncture thereof with the side walls 5 and 6, is turned inward as indicated at 17, to form an indented groove of arcuate cross section in the outer corner portion thereof, which groove, nevertheless, is bounded on one edge by a lateral face diverging outwardly in the direction of the adjacent edge of the plank and joined to a rib 18 having a convex arcuate section, the outer edge of which is spaced from the longitudinal central plane of the board a distance greater than the distance from the bottom of the groove 17 to said plane. Coacting with the groove 17 is a tongue 19 formed as a rounded loop in the sheet of metal which provides the side wall 5 or 6 and the adjacent end section 7 or 10. This tongue 19 is shaped complementarily on its inner side with the groove 17 and rib 18, and preferably is formed with a curved surface of revolution more than a semi-circle in cross-section which makes it possible to use a hard alloy to provide a stiff springiness in the tongue without cracking of the metal in the bending of the sheet to provide the extended tongue. It will be evident from Figs. 1 and 2 that such a tongue and groove 17-19 formed at each opposite face of the board provides not only for an interlocking connection between the boards, but an effectively tight joint therebetween. Furthermore, this joint may be closed and the parts fitted together merely by pressing one board edgewise against the other which will facilitate the assembly, enabling the building

structure to be set up very quickly and without requiring any fastenings between the boards.

One method of assembling the planks at the joint therebetween is illustrated diagrammatically in Fig. 8. The planks 1 and 2 are assembled, for instance, by engaging the tongue 19 at one edge of the plank 2 in the groove 17 of the adjacent edge of the plank 1, and then swinging the planks into transverse alignment as indicated by the arrows. In thus swinging the planks into place, a wedging action is exerted at the joint, whereby the planks snap into place and are held effectively in their assembled relation. Another method of assembling the planks is to interengage them in direct alignment at one end, as, for instance, at the upper corner, and then swing the other end of the plank into place but directly in alignment edgewise, so that a similar wedging action is exerted.

If desired, the joint can be painted to match the surface of the wall, or filled with a mastic or with caulk, as indicated at 20 in Fig. 5, to provide a continuous uniform surface on the wall and to exclude the passage of air or water through the joint.

The board constructed according to this invention is capable of very effective insulation by the incorporation therein of insulating means which will insulate against the passage of heat or cold through the board. This may be provided by incorporating in the board a sheet of insulating material, generally indicated at 21. This insulating material is shown, in the example illustrated, as a bat of rock wool enclosed between paper sheets 22, as illustrated in Fig. 5. The rock wool is usually light and fluffy, so that the bat may be introduced into the board even after it is assembled, if not incorporated during the assembly, by compressing the bat and squeezing it through the space between the diaphragms 14, and then allowing it to expand, as will be evident from Fig. 3. The intermediate diaphragms 14' will retain the bat in place, and it will be held also by expanding edgewise against the end sections of the board. The bat will be suspended in spaced relation from the opposite side walls of the board, so that any condensation which may form thereon will not collect on the bat either to loosen the paper sheets thereof or to injure the insulating qualities of the material.

If the bat is inserted into the board during the fabrication of the latter, it may be held generally by continuing the paper sheets along the edges thereof, as indicated at 22' in Fig. 6, and turning these paper sheets over and around the flange 11 of the joint, between the latter flange and the crimped flange 12, whereby these paper sheets will not only be secured in place by the crimped joint between the side sections of the plank, but the paper in the joint will serve also to insulate the sections against the conduction of heat or cold from one side wall to the other of the plank, which would result from a metal-to-metal contact between these wall sections.

If the edges of the paper are not thus continued through the crimped joint, it is preferred that a separate strip of non-metallic material be incorporated in the crimped joint, as indicated at 23 in Fig. 5. A suitable material found effective for this purpose is an insulating material or tape made of synthetic rubber and sold under the trade name of "Neoprene." Any other suitable material may be used as desired.

Further insulation may be provided, if desired, by a coating 24 on the inner surface of the side

walls, as shown in Fig. 5. This coating is preferably formed by spraying onto the inner side of the formed board section a composition material composed of fluid asphalt containing cork particles and asbestos fibers, and sold under the trade name, "Insulmastic." Such a coating on the inner surface of the side walls will have the additional advantage of preventing the condensation of moisture thereon.

Another method of stopping the transfer of heat from one side to the other of the plank, is illustrated in Fig. 7. In this form, wooden or other heat insulating strips 25 are incorporated in the joint of each plank. These strips are shown as secured by nails 26 to the flanges 11' carried by the side walls 5' and 6', as described above. Two wooden strips are shown incorporated in each edge of the plank, projecting to different extents, as shown in Fig. 7, to overlap corresponding strips in the edge of the connected plank.

In the form shown, the wooden strips 25 support therebetween a sheet of aluminum foil 27 extending along the center of the plank to stop the transfer of heat by reflection. These strips 25 serve not only to support the aluminum, and to prevent the transfer of heat by conduction, but also add to the structural value of the plank when used either as a column or when used as a beam.

In this modified form, the diaphragm stiffeners are indicated generally at 15' in Fig. 7. These are used at intervals along the length of each plank, as described above.

In the further modifications shown in Figs. 9 and 10 the side walls 35 and 35', and 36 and 36' are formed of sheet metal each with a looped spring tongue at one edge of the plank, as indicated at 39, and with a corresponding groove 40 in the opposite edge of the plank to receive said spring tongue. This construction permits the planks to be slipped together and held in resiliently attached relation, as described above.

Instead of securing the inturned edges of the sheet metal sides directly together, these may be connected through interposed strips 41 and 41' which are shown and preferably of wood. These strips 41 and 41' extend lengthwise throughout the length of each edge of the plank. The edge portions of sheet metal are joined thereto as by nails 42 and 42'. These strips 41 and 41' close the edges of the plank between the spaced portions of the sheet metal, as will be evident from Figs. 9 and 10.

Extending transversely of the length of each plank at the opposite sides thereof are stiffener members 43 and 43' also preferably formed of wood. These stiffener members are spaced apart distances of approximately 12 inches or 18 inches along the length of each plank and are in abutting relation with the side walls thereof for stiffening purposes. They are secured in place by nails 44 and 44'.

For insulating effect, the inner face of each side wall of the plank is provided with a lining 45 or 45' of suitable heat insulating material, such, for instance, as "Insulmastic" described above. Moreover, the inner space of the plank is provided with a suitable heat insulating material such as a glass or rock-wool bat indicated generally at 46 in Fig. 9, or one or more strips of aluminum foil indicated at 47 in Fig. 10. The aluminum foil may be glued to the inner edges of the wood stiffeners 43' as well as having the edges thereof secured between the ends of these

stiffeners and the inner face of the strips 41' as shown. As thus constructed it will be evident that the plank will have a layer of insulation at the outer face thereof and succeeding insulation by air space, insulating bat, air space, and insulating lining. In this way effective insulation is provided against the conduction of heat or cold through the plank. The strips 41 and 41' formed of wood or other heat insulating material will prevent the conduction of heat or cold directly between the inturned portions of the metal sides.

The inner lining 45 or 45' serves not only for heat insulating effect but also to stiffen the metal forming the skin or outer surface of the plank as well as to deaden sound. This insulating layer should extend throughout the exposed surface of the plank in use and may be applied throughout the area of the sheet before it is fabricated.

It will be evident from the foregoing description and the accompanying drawings that this construction of plank or building unit may be adapted readily for many different floor plans or building assemblies, and yet will allow such buildings to be manufactured in pre-fabricated construction for ready assembly wherever desired for use. The planks may be used to form different parts of the building, such as the floors, side walls, partitions, ceilings and roof. They may be manufactured to proper size, so that they may be set into place quickly and readily without the necessity for bolting or otherwise securing them by means of fastenings, and yet will be retained effectively in assembled relation.

Moreover, the construction lends itself to effective insulation of the wall or other building part, as may be required in use. It is capable of being finished either at the factory or by the application of any desired finish thereto after assembly. Therefore, it is capable of providing an attractive appearance and at the same time, an effective structure that has many advantages in use.

While the invention is illustrated in certain embodiments, as set forth above, it will be understood that these are described merely for purpose of illustration, and that the invention is capable of other modifications and changes within the scope of the claims, except as hereinafter specifically defined.

I claim:

1. A metal side wall plank comprising spaced opposite side walls of separate elongated flexible metallic sheets, each of the sheets being turned longitudinally back upon itself in an elongated transversely yieldable spring loop and thence laterally of one edge of the plank, said elongated spring loop being formed in an external convex surface of revolution extending through more than a semi-circle and joined by an arcuate section to the laterally extending portion of the sheet, the opposite edge portion of each side wall having an indented groove therein of arcuate cross section with a lateral face diverging outwardly in the direction of the adjacent edge of the plank and turned inwardly through a convex arcuate section laterally of the adjacent edge of the plank, said indented grooves and last-mentioned arcuate sections being substantially complementary to the spring loops for spring engagement by spring loops of an adjacent like plank therewith upon relative swinging motion thereof for yieldably retaining the spring loops of said adjacent like plank thereon, and means connecting said laterally extending portions of said sheets and cooperating therewith forming the edge portion of the plank.

2. A metal side wall plank comprising spaced opposite side walls of separate elongated flexible metallic sheets, each of the sheets being turned longitudinally back upon itself in an elongated transversely yieldable spring loop and thence laterally of one edge of the plank, said elongated spring loop being formed in an external convex surface of revolution extending through more than a semi-circle and joined by an arcuate section to the laterally extending portion of the sheet, each spring loop having one side thereof formed substantially in the plane of the adjacent side wall of the plank, the opposite edge portion of each side wall having an indented groove therein of arcuate cross section with a lateral face diverging outwardly in the direction of the adjacent edge of the plank and turned inwardly through a convex arcuate section laterally of the adjacent edge of the plank, said indented grooves and last-mentioned arcuate sections being substantially complementary to the spring loops for spring engagement by spring loops of an adjacent like plank therewith upon relative swinging motion thereof for yieldably retaining the spring loops of said adjacent like plank thereon, and means connecting said laterally extending portions of said sheets and cooperating therewith forming the edge portion of the plank.

3. A metal side wall plank comprising spaced opposite side walls of separate elongated flexible metallic sheets, each of the sheets being turned longitudinally back upon itself in an elongated transversely yieldable spring loop and thence laterally of one edge of the plank, said elongated spring loop being formed in an external convex surface of revolution extending through more than a semi-circle and joined by an arcuate section to the laterally extending portion of the sheet, the opposite edge portion of each side wall having an indented groove therein of arcuate cross section with a lateral face diverging outwardly in the direction of the adjacent edge of the plank and turned inwardly through a convex arcuate section laterally of the adjacent edge of the plank, said indented grooves and last-mentioned arcuate sections being substantially complementary to the spring loops for spring engagement by spring loops of an adjacent like plank therewith upon relative swinging motion thereof for yieldably retaining the spring loops of said adjacent like plank thereon, and means connecting said laterally extending portions of said sheets and cooperating therewith forming the edge portion of the plank.

4. A metal side wall plank comprising spaced opposite side walls of separate elongated flexible metallic sheets, each of the sheets being turned longitudinally back upon itself in an elongated transversely yieldable spring loop and thence laterally of one edge of the plank, said elongated spring loop being formed in an external convex surface of revolution extending through more than a semi-circle and joined by an arcuate section to the laterally extending portion of the sheet, the opposite edge portion of each side wall having an indented groove therein of arcuate cross section with a lateral face diverging outwardly in the direction of the adjacent edge of the plank and turned inwardly through a convex arcuate section laterally of the adjacent edge of the plank, said indented grooves and last-mentioned arcuate sections being substantially complementary to the spring loops for spring engagement by spring loops of an adjacent like plank therewith upon relative swinging motion thereof for yieldably retaining the spring loops of said adjacent like plank thereon, and means connecting said laterally extending portions of said sheets and cooperating therewith forming the edge portion of the plank.

5. A metal side wall plank comprising spaced opposite side walls of separate elongated flexible metallic sheets, each of the sheets being turned longitudinally back upon itself in an elongated transversely yieldable spring loop and thence laterally of one edge of the plank, said elongated spring loop being formed in an external convex surface of revolution extending through more than a semi-circle and joined by an arcuate section to the laterally extending portion of the sheet, the opposite edge portion of each side wall having an indented groove therein of arcuate cross section with a lateral face diverging out-

wardly in the direction of the adjacent edge of the plank and turned inwardly through a convex arcuate section laterally of the adjacent edge of the plank, said indented grooves and last-mentioned arcuate sections being substantially complementary to the spring loops for spring engagement by spring loops of an adjacent like plank therewith upon relative swinging motion thereof for yieldably retaining the spring loops of said adjacent like plank thereon, means connecting said laterally extending portions of said sheets and cooperating therewith forming the edge portion of the plank, longitudinally spaced stiffener members extending transversely of the length of the plank in bearing relation against the inner faces of the side walls, said stiffener members having inner edges spaced apart in the direction of the thickness of the plank, and insulating material extending in the plank between opposite side walls thereof and between said inner edges of the stiffener members.

5. A metal side wall plank comprising spaced opposite side walls of separate elongated flexible metallic sheets, each of the sheets being turned longitudinally back upon itself in an elongated transversely yieldable spring loop and thence laterally of one edge of the plank, said elongated spring loop being formed in an external convex surface of revolution extending through more than a semi-circle and joined by an arcuate section to the laterally extending portion of the sheet, the opposite edge portion of each side wall having an indented groove therein of arcuate cross section with a lateral face diverging outwardly in the direction of the adjacent edge of the plank and turned inwardly through a convex arcuate section laterally of the adjacent edge of the plank, said indented grooves and last-mentioned arcuate sections being substantially complementary to the spring loops for spring engagement by spring loops of an adjacent like plank therewith upon relative swinging motion thereof for yieldably retaining the spring loops of said adjacent like plank thereon, and strips extending lengthwise of the opposite edges of the plank and connecting said laterally extending portions of said sheets and cooperating therewith forming the edge portion of the plank.

6. A structural joint comprising a pair of metal planks arranged in edge-to-edge inter-

5 connected relation, each of the planks comprising spaced opposite side walls of separate elongated spring metallic sheets, each of the sheets of one plank being turned longitudinally back upon itself in an elongated transversely yieldable spring loop and thence laterally of one edge of the plank, said elongated spring loop being formed in an external convex surface of revolution extending through more than a semi-circle and joined by an arcuate section to the laterally extending portion of the sheet, the adjacent edge portion of the other plank having each side wall sheet thereof formed with an indented groove therein of arcuate cross section with a lateral face diverging outwardly in the direction of the adjacent edge of the plank and turned inwardly through a convex arcuate section laterally of the adjacent edge of the plank, said indented grooves and last-mentioned arcuate sections being substantially complementary to the spring loops of the first-mentioned interconnected plank and having spring engagement therewith upon relative swinging motion thereof for yieldably retaining the spring loops of said first-mentioned 15 plank thereon, and means connecting said laterally extending portions of said sheets of each plank and cooperating therewith forming the edge portion of each plank.
